Specification for Design.

Patented May 24, 1921.

Application filed August 2, 1920. Serial No. 400,871. Term of patent 14 years.

To all whom it may concern:

Be it known that we, WILLIS C. HOLLINS and FRANK P. ARROUSEZ, both citizens of the United States, residing at Los Angeles, in the county of Los Angeles and State of California, have invented a new, original, and ornamental Design for a Combined Fuse and Plug Receptacle Box, of which the following is a specification, reference being had to the accompanying drawing, forming part thereof.

Figure 1 is a front perspective view of a combined fuse and plug receptacle box showing our new design, and

Fig. 2 is a rear view thereof.

The essential feature of our design consists in providing in a combined fuse and plug receptacle box of the character indicated in the drawing, a rectangular case

provided in the outer face of one of its edge walls with an elongate recess and a series of plugging in holes in the recessed wall.

Otherwise than as above indicated, the remaining appearance, outline, construction or ornamentation of an article to which our design has been applied is immaterial as to our design.

We claim:

The ornamental design for a combined fuse and plug receptacle box substantially as shown and described.

Signed at Los Angeles, California, this 23d day of July 1920.

WILLIS C. HOLLINS.
FRANK P. ARROUSEZ.
